COIN OPERATED LOCKS

Edward C. Maurer, St. Paul, Minn.

Application March 28, 1957, Serial No. 649,258

2 Claims. (Cl. 194—32)

This invention relates to an improvement in coin operated locks and deals particularly with a simple and effective lock for use on coin controlled lockers, storage boxes and the like.

In my previously filed application for patent for self service laundry and dry cleaning systems, Serial No. 303,355, filed August 8, 1952, now Patent No. 2,805,747, of which the present application is a continuation-in-part, I described a locker embodying a coin operated lock which was so arranged that the latch bolt thereof could not be moved into locked position unless a coin were first inserted. This general type of lock is useful in various types of storage lockers and the like, the construction being such that the lower key is held from removal until the locker is locked and the locker cannot be locked unless a coin of proper denomination is inserted. The present invention lies in the specific form of lock and in the details of construction thereof.

An object of the present invention resides in the provision of a lock which is extremely simple in form and which can be produced at low cost. In general, the lock includes a latch bolt which is slidable from locked position to unlocked position. The latch bolt is operated by rotation of a suitable key, and the key is constructed so that it can be only removed in one rotative position, that position preferably being when the latch bolt is in 40 locked condition. The latch bolt is provided with a simple projection movable with the latch bolt and forming a part thereof. This projection is engageable with a simple locking lever which is normally in the path of movement of the latch bolt projection. When the latch bolt moves into unlocked position, the projection thereupon is engaged with locking lever and the latch bolt is prevented by this locking lever from reciprocating back into locked position.

The locking lever is balanced in such a manner that it may be swung into disengaged position by the weight of a coin resting thereupon. A coin chute is provided which is capable of delivering a coin into position where the weight of the coin bears against the locking lever. This causes the locking lever to be disengaged from the latch bolt so that the latch bolt may be moved into locked position by the key. As the latch bolt moves into locked position, the coin is released from engagement with the locking lever and may drop into a suitable receptacle.

A feature of the present invention resides in the simplicity of the construction. In order to function as described, few modifications must be made to locks of existing design. To produce the coin actuated lock, it is only necessary to add a projection to the latch bolt, a pivotally supported locking lever, and a coin chute which guides a coin toward this locking lever. As a result, the coin operated locks may be produced at an extremely low cost or production.

A feature of the present invention resides in the simplicity of the coin release. The pivoted locking lever is provided with a generally horizontal arm onto which the coin may be guided. The latch bolt projection nor-

2

mally terminates in a generally horizontal arm portion which is in spaced relation to the arm of the locking lever. The coin chute delivers the coin in such a manner that it engages between the two parallel arms while still 5 partially supported by the lower extremity of the coin chute. The weight of the coin will normally immediately pivot the locking lever into unlocked position. However, if the key has been turned in a manner to engage the end of the locking lever with sufficient friction to 10 prevent pivotal movement of the locking lever, the coin remains suspended until, through operation of the key, the frictional engagement between the latch bolt projection and the locking lever is disengaged, allowing the locking lever to swing out of the path of movement of the 15 latch bolt projection. The latch bolt may then be moved into projected position increasing the distance between the two parallel arms until this distance is greater than the diameter of the coin. The coin then falls by gravity into the coin receptacle.

These and other objects, and novel features of the present invention, will be more clearly and fully set forth in the following specification and claims.

In the drawings forming a part of the specification:

Figure 1 is a perspective view of a portion of a door panel showing the lock with its latch bolt secured in unlocked position, certain hidden portions being omitted for the sake of clarity.

Figure 2 is a view similar to Figure 1, showing the latch bolt in projected position, certain hidden portions being omitted for the sake of clarity.

Figure 3 is a sectional view through the marginal edge of a door showing the relative position of the lock and the cabinet frame into which the latch bolt may extend.

Figure 4 is a front elevational view of the lock itself showing the same in projected position.

Figure 5 is a vertical sectional view through the lock enclosure showing the relation of the latch bolt therein.

Figure 6 is a perspective view of a key which may be used to operate the lock.

Figure 7 is a perspective view of the latch bolt removed from the remainder of the construction.

In my previous application which is above referred to, I disclose a metal locker cabinet having a hingedly supported door and showing the coin operated lock as a means of holding the door closed. The same construction has been illustrated in the present application and slightly greater detail has been illustrated for a better understanding of the lock construction. While the entire locker is not illustrated in the present drawings, a portion of the door panel is indicated in general by the numeral 10, it being understood that this door panel is hingedly supported along the edge parallel with the edge past which the latch bolt extends. As indicated in Figure 3 of the drawings, the door panel 10 is provided with a right angularly extending edge flange 11 which terminates in a reversely turned flange 12 which is parallel to the front panel 10. An inner door closing panel 13 is marginally secured in any suitable way to the flange 12 to enclose the lock. The locker body is indicated in general by the numeral 14 and includes a side wall 15 which is provided at its forward edge with a front flange 16 bent to provide a door frame flange 17 parallel to the locker side wall 15. An outturned flange 19 may be provided on the inner edge of the flange 17 to provide a more finished construction. An aperture 20 is provided in the flange 17 which is designed to accommodate the latch bolt 21 in a manner which will be described in detail.

The lock which forms a part of the present invention is indicated in general by the letter A. The lock A is mounted in a generally rectangular box like housing 22 which is shown as having top and bottom walls 23

and 24, right angularly arranged side walls 25 and 26, and a rear wall 27. Mounting flanges 29 and 30 are secured to the top wall 23 and bottom wall 24 respectively to extend in a common plane and these mounting flanges are apertured as indicated at 31 to accommodate suitable fastening means 32 for securing the lock to the door panel 10. As is indicated in Figure 5 of the drawings, a pair of parallel internally threaded sleeves 33 are mounted upon the back panel 27 to project forwardly toward the door panel 10. A closure plate 34, seen in Figure 4 of the drawings, closes the otherwise open front side of the enclosure 22 and is provided with outwardly projecting ears such as 35 projecting outwardly from the periphery of the plate to engage in corresponding notches such as 36 in the forward edges of the top, bottom and side walls so as to properly locate the plate 34. Machine screws 37 or other suitable means extend through the closure plate 34 and into the sleeves 33 to hold the enclosure assembled.

A forwardly extending tubular enclosure 39 is mounted upon the closure plate 34, the closure plate 34 being normal to the axis of this cylinder 39. Preferably, the cylindrical enclosure 39 is threaded at its rear extremity and threads through the closure plate 34 and is anchored in position by means of a lock nut 40 on the inner side of the closure plate. The cylinder 39 supports an inner rotatable cylinder 41 and suitable mechanism is provided within the cylinder 39 for enabling the cylinder 41 to be rotated when a proper key is inserted. The key 42 includes a hollow cylindrical shank 43 provided at one end with a diametrically extending plate 44 anchored to the sleeve 43 and by means of which the sleeve may be rotated. The sleeve 43 is provided at its end with suitable angularly spaced notches 45 which are designed to interfit with corresponding projections 45' on the cylinder 41 to permit rotation thereof when the proper key is employed. A radially extending lug or ear 46 on the outer surface of the sleeve 43 may pass through a suitable notch 47 in the inner extremity of the hollow outer cylindrical enclosure 39, this notch 47 permitting the key to be inserted when the lug 46 is aligned with the notch 47. The inner surface of the hollow cylindrical enclosure 39 is undercut at 47' so that once the key 42 is inserted and turned, the lug 46 prevents withdrawal of the key until the key is rotated back so that the lug 46 and notch 47 are aligned.

The inner end of the inner cylinder 41 is provided with a pair of shoulders 49 and 50 which are selectively engageable with an arcuate projection 50' on the inner end of the outer cylindrical enclosure 39 to limit pivotal movement of the key in both directions. A pin 51 extends inwardly from the inner end of the cylinder 41 and is eccentrically mounted with respect to the axis of the cylinder 41. This pin 51 is engageable in a slot or notch 52 in the latch bolt 21 so that rotation of the inner cylinder 41 may act to reciprocate the latch bolt 21.

The specific details of the lock mechanism and the manner in which the inner cylinder 41 is rotatably supported is not shown in much detail in the drawings as this arrangement may be varied with different types of locks. From the standpoint of the present invention it is only important to point out that when the key, such as 42, is inserted in the lock and rotated, the latch bolt 21 may be reciprocated from one extreme position to the other. Any lock mechanism which may act through its key to reciprocate the latch bolt may be substituted for the particular arrangement illustrated.

With reference now to Figure 7 of the drawings, it will be noted that the latch bolt 21 is milled from a rectangular bar of metal and the bolt includes a relatively thick projecting portion 53 which is designed to serve as the projecting or locking part of the lock, and the latch bolt also includes an end portion 54 at the opposite end of the lock. Between these ends of the latch bolt, the forward side of the latch bolt is milled

away to provide a generally rectangular notch 55 into which the inwardly projecting end of the cylinder 41 may extend. The slot or notch 52 is positioned to accommodate the eccentric pin 51 and the latch bolt is so proportioned that in one extreme position of the pin 51, the latch bolt is in projected position as shown in Figure 5 of the drawings and in the other extreme position of the pin 51, the latch bolt 21 is in the retracted position illustrated in Figure 1 of the drawings.

As is indicated in Figure 5 of the drawings, the end 53 of the latch bolt 21 extends through a generally rectangular aperture 56 in the housing wall 26. The latch bolt is guided in its movement by the internally threaded sleeves 33 which are spaced a distance proper to permit slidable movement of the latch bolt therebetween. An arm 57 is anchored to the end 54 of the latch bolt and this arm is provided with a right angularly extending arm portion 59 which extends forwardly toward the door panel 10. The right angularly turned extremity 59 is preferably provided with a flattened inner surface 60 for a purpose which will be later set forth. The arm 57 extends through an aperture 61 in the wall 25 of the enclosure 22 as is evident from the various views in the drawings.

A locking lever 62 is pivotally supported upon a pivot 63 extending normally to the surface of the door panel 10. The lever 62 is provided with a right angularly turned ear 64 which terminates in a downturned ear 65 parallel to the surface of the lever 62. The pivot 63 extends through the body of the lever and also through the ear 65, the ear tending to hold the body of the lever in spaced parallel relation to the inner surface of the door panel 10.

The locking lever 62 is provided with an enlarged end 66 which serves as a counter balancing weight tending to rotate the lever 62 in a counterclockwise direction as viewed in Figure 1. An arm 67 extends right angularly from the body of the lever 62, terminating in close proximity to the inner surface of the door panel 10. The lever 62 is provided with a hook end 69 which is designed to hook over the angularly turned end 59 of the arm 57 and to hold the latch bolt 21 from movement. The end of the lever 62 adjoining the hook ends 69 is provided with an inclined cam surface 70 which is engaged by the angularly turned end 59 of the arm 57 as the latch bolt 21 is moved toward unlocked or retracted position. However, in fully unlocked position, the hook ends 69 engages the arm extremity 59 in the manner shown in Figure 1 of the drawings, and when thus engaged, the latch bolt 21 cannot be moved by the key into locking position.

A coin chute 71 is mounted on the inner surface of the door panel 10 and is preferably supported in either vertical or downwardly inclined position as illustrated. The upper end of the chute 71 is provided with an opening which registers with a similar opening in the panel 10 so that coins may be inserted into the upper end of the chute 71. When a coin is placed in the chute 71, it rolls by gravity to the lower end of the chute 71 and is directed to a point between the angularly turned arm 67 on the lever 62 and the angularly turned end 59 of the arm 57. The coin, such as B in Figure 1 of the drawings, is sufficiently large in diameter so that it cannot pass between the arms 66 and 59 when they are in the position shown in Figure 1.

The coin B engages the arm 67 of the lever 62 before the coin is completely out of the chute 71 and the coin is thus retained in an upright position by the chute 71 until the distance between the arm 67 and the angularly turned end 59 of the arm 57 are separated a distance sufficient to permit the coin to drop therebetween. When the weight of the coin rests upon the arm 67, this weight is sufficient to overbalance the weighted lever ends 66 and to cause the lever to swing in a clockwise direction an amount sufficient to disengage the hook 69 from the

arm end 59. When the lever is thus disengaged, the latch bolt 21 may be moved into projected position by the key 42.

During the projecting movement of the latch bolt 21, the arm end 59 moves away from the arm 67 on the lever, and the coin B is free to drop between the arm 67 and the arm end 59 and into a suitable receptacle below. In the particular arrangement illustrated, the door panel 10 is shown as having an inwardly extending flange 72 onto which the coins may drop. Vertically extending plates 73 and 74 tend to confine the coins within a certain area. The inner panel 13 of the door may serve to hold the coins confined until this panel is removed. In actual practice, the panel 13 is provided with a removable part through which the coins may be removed.

It will be seen that the construction described is extremely simple in form and can be added to a locker cabinet at relatively low cost. The lock itself differs from a conventional lock mainly in the provision of the arm 57 with its angularly turned end 59, the pivotally supported locking lever 62, and the coin chute 71. When these parts are secured in proper relationship, it will function as described to prevent the movement of the latch bolt 21 into locking position. In the event an attempt has been made to move the latch bolt 21 prior to the time the coin B is inserted, and in the event that there is a sufficient frictional force engaging the hook end 69 of the lever 62 with the arm end 59, it is possible that the weight of the coin B will be temporarily insufficient to pivot the lever arm 62 as described. In this event, the coin remains resting upon the arm 67. When the operator attempts to lock the locker, if the latch bolt 21 does not move toward projected position upon the turning of the key in one rotative direction, the operator normally will turn the key in the opposite direction. As soon as this is done, the frictional engagement between the arm end 59 and the hook end of the locking lever 62 will be released, and the weight of the coin will pivot the lever downwardly, unlocking the latch bolt and permitting it to move.

In accordance with the patent statutes, I have described the principles of construction and operation of my coin operated locks, and while I have endeavored to set forth the best embodiment thereof, I desire to have it understood that changes may be made within the scope of the following claims without departing from the spirit of my invention.

I claim:

1. A coin actuated lock including a horizontally reciprocal latch bolt, key controlled means for reciprocating said latch bolt between locked and unlocked positions, an arm on said latch bolt terminating in an end portion extending transversely of the direction of movement of said latch bolt, a latch lever having a latch bolt engaging

end projecting upwardly therefrom, means pivotally supporting said latch lever with said latch bolt engaging end extending beneath said end portion of the arm on said latch bolt and engageable therewith to hold said latch bolt in latched position, horizontally directed coin supporting means on said latch lever near said latch bolt engaging end, means biasing said latch bolt engaging end into engagement with said latch bolt, a coin guide above said coin supporting means for directing a coin onto said supporting means acts to pivot said latch bolt engaging end completely out of engagement with said latch bolt due exclusively to the weight of said coin, said coin supporting means being spaced from said end portion of said arm a distance less than the diameter of the coin, and in which the coin is supported between said coin support and said transverse end portion of said arm after the weight of the coin has pivoted said latch lever to release said latch bolt and until said latch bolt is moved out of unlocked position.

2. A coin actuated lock including a horizontally reciprocal latch bolt, key controlled means for reciprocating said latch bolt between locked and unlocked positions, a pivotally supported latch lever having a horizontally directed portion, a lever engaging member on said latch bolt, said latch lever including a latch bolt engaging end extending into obstructive engagement with said lever engaging member, means biasing said latch bolt engaging end of said lever into said obstructive engagement so as to prevent said latch bolt from being moved into its unlocked position, a coin guide terminating above said horizontally directed portion for directing a coin onto said horizontally directed portion so that the weight of said coin will force said horizontally directed portion downwardly to pivot said latch bolt engaging end completely out of engagement with said lever engaging member on said latch bolt, whereby said latch bolt is released for movement by said key controlled means, said horizontally directed portion being spaced from said lever engaging member a distance less than the diameter of the coin, and in which the coin is supported between said horizontally directed portion and said lever engaging member after the weight of the coin has pivoted said latch lever to release said latch bolt and until said latch bolt is moved out of unlocked position.
